UNITED STATES PATENT OFFICE.

GEORGE G. SPENCER, OF CHICAGO, ILLINOIS.

DESIGN FOR A BICYCLE SEAT-POST.

SPECIFICATION forming part of Design No. 33,199, dated September 11, 1900.

Application filed September 23, 1899. Serial No. 731,498. Term of patent 7 years.

To all whom it may concern:

Be it known that I, GEORGE G. SPENCER, a citizen of the United States, residing at Chicago, in the county of Cook and State of Illinois, have invented and produced a new and original Design for Bicycle Seat-Posts, of which the following is a specification, reference being had to the drawing forming a part thereof.

Figure 1 is a side elevation of a post built after my design. Fig. 2 is a plan view of such a post, and Fig. 3 a rear elevation of the same.

As shown in the drawings, the leading or material feature of my design consists in the form or configuration of a bicycle seat-post in L form, the main stem A having the in-

gral top or branch B extending from its upper end and uniting therewith in curving lines. The branch B is of a diameter less ²⁰ than that of the main stem A. The top of the main stem A is in neck form, somewhat similar in appearance to the top of a vial, said neck rising above the top line of the branch B. This neck C is provided with a central ²⁵ opening D.

I claim as my invention—

The design for a bicycle seat-post substantially as shown and described.

GEORGE G. SPENCER.
